ELECTRICAL THERMOSTAT

Jean R. Fortier, South Orange, N.J., and Paul S. Martin, Flushing, N.Y., assignors to Federal Pacific Electric Company, Newark, N.J.

Filed June 3, 1971, Ser. No. 149,871

Term of patent 14 years

Int. Cl. D10—04

U.S. Cl. D52—7

FIG. 1

FIG. 2

FIG. 3

FIG. 4

FIG. 1 is a front perspective view of an electrical thermostat showing our new design;

FIG. 2 is a rear elevational view thereof;

FIG. 3 is a right side elevational view, the left side being a mirror image thereof; and

FIG. 4 is a top plan view thereof.

We claim:

The ornamental design for an electrical thermostat, substantially as shown and described.
